US00D908425S

(12) **United States Design Patent** (10) Patent No.: **US D908,425 S**
(45) Date of Patent: ** Jan. 26, 2021

(54) **BOTTLE LID**

(71) Applicant: **EVERICH AND TOMIC
HOUSEWARES CO., LTD.**, Zhejiang
(CN)

(72) Inventor: **Huajun Yao**, Zhejiang (CN)

(73) Assignee: **EVERICH AND TOMIC
HOUSEWARES CO., LTD.**, Zhejiang
(CN)

(**) Term: **15 Years**

(21) Appl. No.: **29/687,275**

(22) Filed: **Apr. 11, 2019**

(30) **Foreign Application Priority Data**

Oct. 12, 2018 (CN) 2018 3 0569012

(57) **CLAIM**

The ornamental design for a bottle lid, as shown and described.

DESCRIPTION

FIG. 1 is a front elevational view of a bottle lid, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top front perspective view thereof;

FIG. 8 is a top rear perspective view thereof, with the nozzle feature in an open position; and,

FIG. 9 is a bottom perspective view thereof.

1 Claim, 9 Drawing Sheets
